CLAIM

The ornamental design for a track for a mobile shelving system, shown and described.

DESCRIPTION

FIG. 1 is a perspective view of a track for a mobile shelving system, showing my new design, shown broken away to indicate indeterminate length;

FIG. 2 is a fragmentary top plan view thereof;

FIG. 3 is an end elevational view thereof, the opposite end being identical thereto;

FIG. 4 is a fragmentary front elevational view thereof;

FIG. 5 is a fragmentary rear elevational view thereof;
and

FIG. 6 is a fragmentary bottom plan view thereof.

FIG. 2

FIG. 4

FIG. 3

FIG. 5

FIG. 6
